RADIATOR CONSTRUCTION

William C. Klespe, Beloit, Wis., assignor to Yates-American Machine Company, Beloit, Wis., a corporation of Delaware

Application March 26, 1937, Serial No. 133,127

6 Claims. (Cl. 293—54)

The present invention has to do with radiators of the type used in connection with internal combustion engines.

The purpose of the invention is to provide a radiator of improved construction which is light, strong, rigid and durable, and is quite inexpensive to manufacture.

The invention resides particularly in the construction and arrangement of the protective grill with respect to the other structural elements which together constitute the radiator. In the hereinafter described embodiment of the invention this grill is a one-piece sheet metal member which is provided with a forwardly protruding front portion and rearwardly extending side portions. The front portion, which may be either V-shaped or bowed in horizontal section, forms a protective guard for the cooling core behind the same, provides a support for the front portion of the upper tank, and leaves an opening behind the same, accessible from the bottom of the unit, for giving access to the front of the core for cleaning. The rearwardly extending sides of this one-piece sheet metal member embrace certain of the other parts of the radiator and are secured to the same in such a way as to form a well reinforced unit.

Other advantages of the assembly as herein-after set forth will appear to those skilled in the art of motor cooling systems.

In order that the invention may be readily understood there is set forth in the accompanying drawings and in the specification predicated thereon a preferred embodiment of the same, it being understood that the description and claims based thereon are not to be taken in an unnecessarily restricting sense.

In the drawings

Fig. 1 is a front elevation of the assembly;

Fig. 2 is a side elevation of the same;

Fig. 3 is a horizontal section on the line 3—3 of Fig. 1;

Fig. 4 is a vertical section on the line 4—4 of Fig. 1;

Fig. 5 is a detail elevation of the grill;

Fig. 6 is a side elevation of the grill; and

Fig. 7 is a top plan of the grill.

Having particular reference to the drawings, there is shown a radiator at 11 with an upper water tank 12, cooling pipes 13 with associated cooling fins 14 together comprising a cooling core, a lower tank 12a, an outlet tube 15 leading from the cooling core and a return pipe 16 to the tank 12. Tank 12 has a forward extension 17 which overhangs the space in front of the cooling core.

A sheet metal grill 18 has its central portion 19 bent to a forwardly convex shape and provided with apertures to give the grill effect, as indicated at 20, and has its two sides 21 angularly bent into parallel relationship with the terminal edge of rebent at 22. Intermediate the extent of each of the side flanges is a rib 23 outwardly convex and inwardly concave. The front 19 of the grill is at the top inwardly bent to form narrow horizontal flanges 24 while the side flanges 21 extend upwardly beyond the front 19 as flanges 25 in a common plane with the sides.

The upper tank 12 has impressed thereon at each side beads 26 which are outwardly convex and inwardly concave and adapted to be telescopically associated with the beads 23 of the grill side flanges 21, thus serving to position and retain the upper tank and the side flanges of the grill in relative position when the grill is disposed with its flanges 24 beneath and in supporting relationship to the forward extension 17 of the upper tank with its side flanges 21 disposed at the sides of and forming a housing for the cooling core. In this position the flanges 24 are secured as by spot-welding or soldering or any other approved manner to the lower edge of the tank extension 17 while the flanges 24 are likewise spot-welded, soldered or otherwise rigidly affixed to the sides of the tank. Embracing the lower ends of the assembly, extending the full width thereof, is a band or strap 27 having its upturned edges 28 secured as by spot-welding or otherwise. This band 27 has depending therefrom screw studs 29 by means of which the assembly is secured to the chassis.

It will be observed that the forming of the grill 18 as forwardly convex, curved or V-shaped, not only enables the capacity of the tank 12 to be increased to the extension of the overhanging forward extension 17 but also provides a lower opening at 30 which gives access to the space between the grill and the cooling core for cleaning the latter of accumulated foreign matter.

Thus it will be seen that by reason of the characteristic assembly of the protective grill with the tank and the cooling core is attained an efficient cooperative relationship precluding vibration, loosening of the elements in use, and increase in the tank capacity, easy cleaning of the cooling core and, with all, a pleasing appearance as an entirety.

I claim:

1. In radiator construction, the combination with top and bottom tanks and circulating core elements, of means for rigidly connecting the

tanks comprising a sheet metal stamping of generally U-shaped horizontal section, the sides of which stamping are secured to the sides of both tanks and the front of which is disposed in forwardly spaced relation to the core elements.

2. In radiator construction, the combination with top and bottom tanks and circulating core elements, of means for rigidly connecting and supporting the tanks comprising a one-piece sheet metal stamping of generally U-shaped horizontal section, the sides of which stamping are positioned against and secured to the sides of both tanks and the front of which is perforated as a grill and disposed in forwardly spaced relation to the core elements.

3. In radiator construction, the combination with top and bottom tanks and circulating core elements, of means for rigidly connecting the tanks comprising a sheet metal stamping of generally U-shaped horizontal section, the sides of which stamping are secured to the sides of both tanks and the front of which is disposed in forwardly spaced relation to the core elements and is secured to the front of the upper tank.

4. In radiator construction, the combination with top and bottom tanks and circulating core elements, of means for rigidly connecting and supporting the tanks comprising a one-piece sheet metal stamping of generally U-shaped horizontal section, the sides of which stamping are secured to the sides of both tanks and the front of which is perforated as a grill and disposed in forwardly

spaced relation to the core elements, the front of said stamping being secured to the under side of the front of the upper tank in vertical supporting relation.

5. In radiator construction, the combination with top and bottom tanks and circulating core elements, of means for rigidly connecting the tanks comprising a sheet metal stamping of generally U-shaped horizontal section, the sides of which stamping are secured to the sides of both tanks and the front of which is disposed in forwardly spaced relation to the core elements, the top of the front of said stamping being rearwardly flanged and underlying the under side of the front of the upper tank in vertical supporting relation.

6. In radiator construction, the combination with top and bottom tanks and circulating core elements, of means for rigidly connecting and supporting the tanks comprising a one-piece sheet metal stamping of generally U-shaped horizontal section, the sides of which stamping are secured to the sides of both tanks and the front of which is perforated as a grill and disposed in forwardly spaced relation to the core elements, the front of said stamping being of V-shaped horizontal section, with the center of the same farthest removed from the core elements, and the top of the front of said stamping being rearwardly flanged and underlying the under side of the front of the upper tank in vertical supporting relation.

WILLIAM C. KLESPE.
